UNITED STATES PATENT OFFICE.

NICHOLAS S. VEDDER, OF TROY, AND TOBIAS S. HEISTER, OF LANSINGBURG,
ASSIGNORS TO JASPER VAN WORMER AND MICHAEL McGARVEY, OF ALBANY, NEW YORK.

DESIGN FOR A COOKING-STOVE.

Specification forming part of Design No. 5,162, dated August 1, 1871.

To all whom it may concern:

Be it known that we, NICHOLAS S. VEDDER, of the city of Troy, in the county of Rensselaer and State of New York, and TOBIAS S. HEISTER, of Lansingburg, in the said county and State, have jointly invented and produced a new Design for Stoves and Ranges, of which the following is a specification, reference being had to the accompanying photographic representation of a cooking-stove having our said design.

One part of our invention consists of the compound ornament A, shaped and arranged upon a door or plate of a stove or range so as to appear substantially as shown in the accompanying photograph. Another part of our new design consists of the compound ornament B, shaped and arranged upon a door or plate of a stove or range so as to present substantially the same appearance as is represented in the aforesaid photograph. Another part of our design consists of the ornamental border C, shaped and arranged upon a door or doors, or plate or plates, of a stove or range, substantially as shown in the photograph. Another part of our invention consists in the combination of the compound panel ornament A and ornamental border C, all shaped and arranged together upon a door or plate of a stove or range so as to appear substantially as shown in the aforesaid photograph, with or without the intervening molding d. Another part of our invention consists of the combination of the central ornament B and ornamental border C, shaped and arranged together upon a door or plate of a stove or range so as to appear substantially as represented in the photograph. Another part of

our invention consists of the combination of the ornamental border C and central ornament E, both shaped and arranged together upon a plate of a stove or range substantially, as shown in the photograph aforesaid. Another part of our invention consists of the design for the leg F, as distinguished by the central ornament g, swelling surface h, and ornamentation i, all shaped and arranged upon the upper portion of the leg as shown in the photograph.

What we claim as our invention is—

1. The ornament A, shaped and arranged on a door or plate of a stove or range, as herein described.
2. The ornament B, shaped and arranged as herein described.
3. The ornamental border C, shaped and arranged as herein described.
4. The combination of the ornament A and border C, shaped and arranged as described, with or without an intervening molding, d.
5. The combination of the ornament B and border C, shaped and arranged as herein set forth.
6. The combination of the ornamental border C and central ornament E, shaped and arranged together as herein described.
7. The design for the foot or leg F, as described.

NICHOLAS S. VEDDER.
TOBIAS S. HEISTER.
